US00D629525S

(12) **United States Design Patent**
Ladwig et al.

(10) **Patent No.:** **US D629,525 S**
(45) **Date of Patent:** **** Dec. 21, 2010**

(54) **HAND PIECE FOR ULTRASOUND THERAPY HEAD**

(75) Inventors: **Jeffrey William Ladwig**, Seattle, WA (US); **Joshua Kornfeld**, Seattle, WA (US); **Jared Randall**, Seattle, WA (US); **Austin R. Porter**, Seattle, WA (US); **Travis J. Hosler**, Seattle, WA (US)

(73) Assignee: **Medicis Technologies Corporation**, Bothell, WA (US)

(**) Term: **14 Years**

(21) Appl. No.: **29/363,081**

(22) Filed: **Jun. 4, 2010**

(51) LOC (9) Cl. **24-02**

(52) U.S. Cl. **D24/187**

(58) **Field of Classification Search** D24/107, D24/141, 158, 164, 165, 167, 170, 186-187, D24/231; D10/57, 60, 78, 80; 600/407, 600/461, 459; 378/98.7, 98.8, 189

(57) **CLAIM**

The ornamental design for hand piece for ultrasound therapy head, as shown and described.

DESCRIPTION

FIG. 1 is a front perspective view of a hand piece for ultrasound therapy head showing my new design;

FIG. 2 is a rear perspective view;

FIG. 3 is a front elevational view;

FIG. 4 is a rear elevational view;

FIG. 5 is a right elevational view;

FIG. 6 is a left elevational view; and,

FIG. 7 is a top plan view.

The broken line showing is for illustrative purposes only and forms no part of the claimed design.
